INVENTOR
Martin Hauser
BY *Arthur C. Brown*
ATTORNEY

UNITED STATES PATENT OFFICE.

MARTIN HAUSER, OF KANSAS CITY, MISSOURI.

STEAM-PIPE CASING.

Application filed July 3, 1925. Serial No. 41,448.

This invention relates to steam pipe casings; that is, to casings for insulating steam pipes which convey steam from a central source of supply to a distant point of consumption.

It is common practice in dense residential districts and the like to supply a number of buildings with steam for heating purposes from a central power plant. The steam pipes are usually embedded in the ground and for their protection as well as for insulation it is preferable to carry them in casings or conduits so I have provided a novel form of casing or conduit to receive the pipes to thereby prevent heat losses and eliminate liability of excessive deterioration.

The novel features of my invention will be understood by reference to the following description in connection with the accompanying drawings, in which—

Fig. 1 is a perspective view of a casing in a trench carrying a steam pipe, parts being broken away to better illustrate other parts.

Fig. 2 is a disassociated, sectional view of the base member and the cover, the pipe being also shown in section.

Fig. 3 is a sectional view through the base and cover as well as the pipe, the cover and base being shown as connected, and

Fig. 4 is a perspective view of the base and the cover.

The base member is preferably constructed of sheet metal. It is shown as comprising a trough-shaped member 1 having its edges bent downwardly and then upwardly as at 2 and 3 to form grooves 4 and 5 to receive the lower edges 6 and 7 of the arched metallic cover 8, the cover being preferably corrugated. The joints 9 and 10 between the bottom edges of the cover 8 and the bottoms of the grooves 6 and 7 are preferably sealed with a cementitious material, as indicated at 11 and 12. The upper edges of the side walls 13 and 14 of the trough-shaped member 1 receive stirrups 15 and 16 which are in the form of U-shaped straps having their ends bent over the edges of the side walls and their intermediate portions provided with bearings 17 and 18 to receive the journals 19 and 20 of the rollers 21 which are supported above the floor of the base.

The proportions of the base and cover are such that the casing is considerably larger than the insulated steam pipe 22, which is

supported on the rollers so that there is a dead air space 23 between the casing and the steam pipe.

The cover is preferably secured to the base by tie members shown as wires 24, which are threaded through the holes 25 in the base and embrace the cover 8.

The base is preferably sectional in that it may be made up of a plurality of lengths, each section overlapping the other, as indicated at 26. The cover may be made up of sections of proper length which provide break joints with respect to the sections of the base. The casing may preferably be arranged in a trench 27 of appropriate depth.

The base will be first placed in the bottom of the trench; then the stirrups with the rollers will be located and the steam pipe laid upon the rollers; after which cementitious material may be flowed into the grooves at the sides of the trough-shaped member 75 and the cover put in place and tied if need be by the binding members 24 so that an airtight seal will be provided between the cover and the base. Then earth may be covered over the casing in the usual way.

It will be observed that the side walls 13 and 14 are higher than the outer walls of the grooves 4 and 5. Therefore, should any water accumulate in the grooves 4 and 5, it will flow over the side edges of the outer walls before it can enter the trough; consequently, liability of water entering the trough will be entirely eliminated.

It will be apparent that the casing is simple in construction, that it may be easily applied in the trench, and that it will efficiently protect the pipe and insulate it from loss of heat.

What I claim and desire to secure by Letters Patent is:

1. A steam pipe casing comprising a trough-shaped base of sheet metal having its side edges bent to provide edge grooves, an arch-shaped cover received in said edge grooves, cementitious material in the edge grooves, tie members for fastening the cover to the base, stirrups carried by the edges of the grooved portions of the base, and pipe supporting rollers above the floor of the base supported by the stirrups.

2. In a steam pipe casing, a metallic bottom section having side edge portions and a depressed central portion providing a

- trough, means within the trough for supporting a pipe, an arched cover having depending side edge portions, the edge portions at each side of said bottom section having flanges and upstanding portions spaced from each other to form grooves receiving said depending edge portions to provide interfitting joints and cementitious material in the joints between said bottom section and cover.
- 10 3. In a steam pipe casing, a trough-shaped base having extending side edges, stirrups detachably suspended from the upstanding side edges of the base, bearings on

said stirrups, rollers having journals seating in said bearings, and a cover for said base.

4. In a steam pipe casing, a base formed of sheet metal to provide a central trough and side grooves, stirrups suspended from the edges of the trough and comprising bearings, rollers having journals supported in 20 bearings of opposite stirrups, and an arched cover having edge portions seated in said grooves.

In testimony whereof I affix my signature.

MARTIN HAUSER.
